Primary Examiner—A. Hugo Word*Assistant Examiner*—Robin V. Taylor*Attorney, Agent, or Firm*—Poms, Smith, Lande & Rose[57] **CLAIM**

The ornamental design for a double-walled plastic compactor cover, as shown and described.

DESCRIPTION

FIG. 1 is a top plan view of my double-walled plastic compactor cover;

FIG. 2 is a front elevational view, the rear elevation view being a mirror image thereof;

FIG. 3 is a right side view, the left side being a mirror image thereof;

FIG. 4 is a bottom plan view thereof;

FIG. 5 is a cross section view taken on line 5—5 of FIG. 1 thereof;

FIG. 6 is a cross section view taken on line 6—6 of FIG. 1 thereof;

FIG. 7 is a top plan view of an alternative embodiment of my invention; and,

FIG. 8 is a cross section view taken on line 8—8 of FIG. 7 thereof.

FIG. 1

FIG. 2

FIG. 3

FIG. 4

FIG. 5

FIG. 6

FIG. 7

FIG. 8
